SCALPEL BLADE HOLDER

George A. Montelius, P.O. Box 53, Rte. 1,
Braham, Minn. 55006

Filed Feb. 9, 1966, Ser. No. 982

Term of patent 3½ years

(Cl. D83—12)

FIG. 1 is a top plan view of a scalpel blade holder, embodying my new design;

FIG. 2 is a front elevation thereof;

FIG. 3 is a bottom plan view thereof;

FIG. 4 is a cross-section taken on line 4—4 of FIG. 3; and

FIG. 5 is a modified embodiment of the blade holder shown in FIG. 1, the front, bottom and cross-section correspond to FIGS. 2, 3 and 4 respectively.

The dominant features of my design reside in the portions shown in full lines.

I claim:

The ornamental design for a scalpel blade holder, as shown and described.
